UNITED STATES PATENT OFFICE

ALBERT I. ELIAS, OF LONG BEACH, NEW YORK, ASSIGNOR TO WISE SHOES, INC., OF NEW YORK, N. Y., A CORPORATION OF NEW YORK

DESIGN FOR A STORE FRONT

Application filed August 15, 1929. Serial No. 32,414. Term of patent 3½ years.

To all whom it may concern:

Be it known that I, ALBERT I. ELIAS, a citizen of the United States of America, and resident of Long Beach, county of Nassau, and State of New York, have invented a certain new, original, and ornamental Design for Store Fronts, of which the following is a specification, reference being had to the accompanying drawing, forming part thereof.

In the drawing:

Fig. 1 is an elevation of a store front showing the design; and

Fig. 2 is a horizontal section of the same, with the entry floor in plan.

The dominant feature of this design is the general configuration of the store front proper, aside from the checkered floor.

I claim:

The ornamental design for a store front as shown and described.

ALBERT I. ELIAS.
